UNITED STATES PATENT OFFICE.

HENRY E. TRUMBLE, OF KALAMAZOO, MICHIGAN.

WATER-MOTOR.

SPECIFICATION forming part of Letters Patent No. 394,740, dated December 18, 1888.

Application filed August 17, 1888. Serial No. 283,000. (No model.)

To all whom it may concern:

Be it known that I, HENRY E. TRUMBLE, a citizen of the United States, residing at Kalamazoo, county of Kalamazoo, State of Michigan, have invented a new and useful Water-Motor, of which the following is a specification.

This invention relates to another motor invented by me and disclosed in an application filed March 27, 1888, Serial No. 268,668, in which application a jointed piston was shown pivoted to a support or in a flume, and adapted to be oscillated by the flowing water, and by that means operate a crank-shaft at its pivoted end.

The object of the present invention is to construct a motor on a similar principle provided with automatic exhaust-valves, as below described.

In the drawings forming a part of this specification, Figure 1 is the motor with one wall removed and parts in section on line 1 1 in Fig. 4; Fig. 2, a section on line 2 2 in Fig. 1, looking from a point below; Fig. 3, a section on line 3 3, looking from a point at the left; Fig. 4, a view of the slide in Fig. 1, with the part D in cross-section near its lower end; Fig. 5, an edge view of Fig. 4; and Fig. 6 is an enlarged perspective of a part pointed out by like letters in Fig. 1.

Referring to the lettered parts of the drawings, B is a flume through which the water or any other suitable element of power flows in the direction from the upper to the lower ends in Fig. 1. The piston is composed of two parts, D D', hinged together end to end. The other end of part D is rigidly attached to a slide, C, and stands and moves in a position parallel with the line of the flowing water. The other end of the part D' is left free near the induction-port of the flume. (See upper end, Fig. 1.)

The slide C has bearings in the flume transversely to the plane of the piston. Water entering the induction-port at the left of the piston in Fig. 1 will carry the piston and slide over to the right side of the flume, where they will occupy a position in relation to the flume like the one shown at the left side in Fig. 1. In this figure the piston and slide have just reached the position they occupy. The right-hand gate or valve, a, hinged to the slide C, and adapted to close one of two exhaust-ports

in said slide, has been released from contact with the right-hand roller, U, and the water is supposed to be exhausting through this open port. As soon as this exhausting of water begins, the free end of part D' of the piston is tilted over by the action of the water to the place it occupies in Fig. 1, against the right wall of the flume B, near the induction-port, thus shutting the flow of water from the right side of the piston and directing its course into the left of the flume, when, as before stated, the piston and slide will be carried to the right. As soon as the open valve a contacts with its roller U, it will close, and during the right-hand movement of the slide the other valve a (closed in Fig. 1) will be released and the water at the left of the piston will exhaust, and the free end of the piston will tilt over against the left wall of the flume. Thus the action continues automatically by the action of the water, the piston moving from one side of the flume to the other, the oscillating free end forming a cut-off, and the slide reciprocating in the slide - bearings. Power might be transmitted by connecting other machinery with the slide C, or by means of a crank-shaft, b, bearing a crank, F, to which crank a connecting-rod is attached. (See P, Fig. 2.)

The crank-shaft has bearings in the flume B, Figs. 1, 2, and 3, and radiating from it is a lever, A, the free end of which is loosely connected with the slide C by being entered between the lugs x x of slide C, Figs. 1, 3, and 5. Thus when the slide reciprocates, the lever A of the crank-shaft d oscillates, giving motion to the crank F. During the action the end of the lever A of course is drawn partly out and in the space between the lugs x x, which is equivalent to a lengthening and shortening of said lever.

In some instances the exhaust-valves a will be released too soon. To provide for this I employ a trip-lever, c, pivoted to the crank-lever A, Fig. 1, and a sliding-plate, r, having projections S S at an angle to said plate, and in use parallel to and contacting with the slide C, Figs. 1, 3, and 6. One end of the trip-lever c is coupled with the slot of plate r in like manner as the end of lever A in the slot of the slide C, Figs. 1, 2, and 3. During the operation one of the projections S catches over the edge of

one of the valves *a*, first one and then the other. The free end of the trip-lever *c* comes in contact with a lug, *e*, of the wall of the flume, Figs. 1 and 2, and this trips the sliding plate 5 *r* and releases the valve *a*. In Fig. 1 the right-hand valve has just been released and as soon as the parts change their positions the end of lever *c* will contact with the other stud *e* and release the other door or valve *a*; but I do not limit the invention to this mode of holding and releasing the valves *a*, for it will doubtless only be contingently needed. Neither do I wish to limit the machine to the use as a motor, for the flume with the piston 15 may be employed in a meter.

The motor need not employ the slide *C*, having exhaust-ports and valves; but it is desirable in order to gain power and economize in the use of water.

20 Having thus described my invention, what I claim is—

1. The combination of the flume, the transverse exhaust-port slide having the automatic exhaust-valves and the jointed piston 25 rigidly attached at one end to the slide and at right angles thereto in the plane of the flowing stream, substantially as set forth.

2. The combination of the flume, the exhaust-port slide transversely in the flume, the 30 jointed piston at right angles to the slide, a crank-shaft, and a radial arm attached to the shaft at one end and loosely connected with the slide at the other end, substantially as set forth.

35 3. The combination of a suitable flume, the jointed piston, a slide having the exhaust-

ports, valves hinged in said ports, and the rollers with which the valves come in contact to close them, said piston being in the plane of the flowing element of power through the 40 flume and the slide transversely thereto, substantially as set forth.

4. The combination of a suitable flume, a slide having the exhaust-ports, valves in said ports, the rollers with which the valves come 45 in contact to close them, the jointed piston, and a crank-shaft provided with a radial arm, the free end of said arm being attached to the slide, imparting an oscillating movement to the arm by the reciprocating movement of 50 the slide, said piston and slide being at right angles to each other in the flume, with the free end of the piston in the induction-port, substantially as set forth.

5. The combination of a flume, the valves, 55 and the transverse slide having the ports in which the valves are hinged, the jointed piston at right angles to the slide, the rollers for closing the valves, a crank-shaft having the radial arm oscillated by said slide, the trip-slide for holding and releasing the valves, the pivoted lever for operating said trip-slide, said lever being carried by the radial arm, and the studs with which said pivoted lever comes in contact, substantially as set forth. 60 65

In testimony of the foregoing I have hereunto subscribed my name in presence of two witnesses.

HENRY E. TRUMBLE.
